J. P. Osborn,
Making Staves.

No 11,136.

Patented June 20, 1854.

UNITED STATES PATENT OFFICE.

JAMES P. OSBORN, OF STAUNTON, NEW JERSEY.

METHOD OF TURNING CASKS, &c., FROM SOLID PIECES.

Specification of Letters Patent No. 11,136, dated June 20, 1854.

To all whom it may concern:

Be it known that I, JAMES P. OSBORN, of the village of Staunton, in the county of Hunterdon, State of New Jersey, have invented a new and useful Improvement in Making Barrels, Casks, Tubs, &c.

The nature of my improvement consists in cutting the bodies of barrels out of blocks of wood, without injuring the cores, by means of longitudinal knives, connected with cross-heads, and fed by screws.

To enable others, skilled in the art, to make and use my invention, I will proceed to describe its construction and operation, reference being had to the annexed drawings forming part of this specification, in which—

Figure 1 is a top view of my machine. Fig. 2, a bottom view. Figs. 3 and 4 views 20 of side and cross-heads.

Similar letters refer to like parts.

A is the frame; B B', spindle; C C', carriers; D D', longitudinal tool-bearers; E E', cross-heads; F F', guide-rests; G G', guide-pieces; H, set-screws; I, feed-screws; L L, bearer; M, jam-nut; N, jam-nut; O, jam-nut; P, bearer; Q, groove; R, connecting-rods; S, bearer; T, gear-wheels; U, pinion; W, slide; K, jam-nut; Y, bearing-pins.

The feed-screws, I, being connected with the gear-wheels T, revolve with them, and, consequently, give a longitudinal motion to the cross-heads, E E'. The gear-wheels T, give motion to the pinion, U, to which the spindle, B, is attached. One end of the knife, D, rests in the slide W. This slide runs in the groove Q. The slide W is attached to the cross-pieces G which are regulated by the set-screws H. The other end 40 of the tool-bearer, D, passes through the guide-rest F. The block out of which the barrel, cask or tub is to be turned, is sustained by the carriers C C', which are screwed up or relieved by means of the nuts 45 K, M, N, O.

Motion being communicated to the gear-wheels T, the cross-head E is carried forward, and the cutter on the opposite end of the tool-bearer D enters the end of the block 50 and cuts in as fast as fed by the screws I. The cross-head, E, is connected with another cross-head, E', on the opposite end of the machine, by means of the connecting-rods R. The tool-bearer, D, cuts to the center of the block, when the motion of the gear-wheels is reversed, and the knife withdraws.

On reversing the motion of the feed-screws I, the cross-piece E' is carried in an opposite direction, so that the tool-bearer D' enters and cuts upon the end of the block opposite to that which has already been cut, and in the meanwhile the tool-bearer D' is being withdrawn from the cavity it has already turned. The guide-rests F F', it will be observed, are divided by oval-shaped separations. This particular form is given, so that the tool-bearers may cut out barrels having bulges.

In the large machine it is intended that the tool-bearers shall be placed between every other one of these separations, on the guide-rests, in order that as many different barrels may be turned from the same block at one operation. When it is desirable to turn straight-sided vessels the separations 75 on the guide-rests F F' are made straight-sided, and the tool-bearers made to move in horizontal lines.

The chimes of the barrels are turned by means of a suitable tool, resting upon the bearer S. By means of the slide W, running in groove Q, together with cross-pieces G, and set-screws H, the position of the tool-bearer D may be changed, in order to cut in a straight line, or at an angle, so as 85 to give the required bulge to the barrel.

The mode of changing the position of the tool-bearer D' is somewhat different. The tool-bearer D' rests in the cross-head E'. The cross-head E' is slotted, having cross-pieces G' passing through. By means of set-screws H' the cross-pieces G' are regulated, and with them the cross-head E' is moved either to the right or to the left; and thus a corresponding position is imparted to 95 the tool-bearer D'.

By my improvement I am enabled to turn the bodies of barrels in one piece from the solid blocks, whereby I think I can produce them cheaper, and in a superior manner, 100 than they can be made from staves, and put together. There is no wasting of material, since by putting on a sufficient number of tool-bearers and cutters I can produce several barrels, or tubs, one within another, 105 each of a smaller size, at one operation. After the bodies of my barrels are thus turned, and the chimes cut, I fit in the heads, and then hoop them in the usual manner. For tight barrels, water-casks, tubs, kegs, 110 and wooden vessels, of every description my improvement is peculiarly applicable.

I do not claim the making of the bodies of barrels, casks, tubs, &c., by turning them in one piece out of the solid block; but

I claim—

- 5 1. The tool-bearers, D D', cutting in contrary directions in combination with the cross-heads, E E', in the manner and for the purposes, substantially, as described.
2. I claim the combination of the cross-
10 heads, E E', with the connecting-rods, R,

and feed-screws, I, in the manner and for the purposes, substantially, as described.

3. I claim the method, substantially, as herein described, of adjusting the position of the tool-bearers D D'.

JAMES P. OSBORN.
